UNITED STATES PATENT OFFICE.

MICHAEL E. BRENNAN, OF HUDSON, NEW YORK.

CHIN-SUPPORT.

1,397,499.

Specification of Letters Patent. Patented Nov. 22, 1921.

Application filed May 24, 1921. Serial No. 472,150.

To all whom it may concern:

Be it known that I, MICHAEL E. BRENNAN, a citizen of the United States, residing at Hudson, in the county of Columbia and State of New York, have invented new and useful Improvements in Chin-Supports, of which the following is a specification.

This invention relates to appliances for use by undertakers, and has for its object 10 the provision of a device for properly supporting the chin and lower jaw of a corpse so as to hold these parts rigid and in the correct position to permit effective circulation of the embalming fluid.

15 Another object is the provision of a device of this character which is readily adjustable for use upon corpses of different sizes and for enabling the chin and consequently the head to be tilted to any desired position, the device being furthermore not displeasing in appearance and being also capable of folding into a small compass so as to occupy but little space in an undertaker's kit bag.

20 An additional object is the provision of a device of this character which will be simple and inexpensive in manufacture, easy to apply and adjust, highly efficient in use, durable in service, and a general improvement in the art.

With the above and other objects and advantages in view, the invention consists in the details of construction to be herein-after more fully described and claimed and 35 illustrated in the accompanying drawings in which—

Figure 1 is a side elevation of my device in applied position,

Fig. 2 is a front elevation thereof de- 40 tailed, and

Fig. 3 is a sectional view on the line 3—3 of Fig. 2.

Referring more particularly to the drawings, I have shown my device as comprising a yoke 10 which is formed of two similar curved rod or heavy wire sections 11 formed at one end with interengaging eyes or loops 12 whereby the two sections may be folded together when the device is not in use. Associated with the other end of the yoke is a cross bar 13 which is formed with holes 14 for the passage of the arms of the yoke, set screws 15 being threaded into the ends of this cross bar and engaging the yoke arms 50 whereby to hold the bar rigid.

Rotatably mounted upon the cross bar 13 and slidably therealong, is a block member 16 formed with a transverse hole 17 through which is slidably adjustably mounted the shank 18 of a chin rest proper which is 60 provided at one end with a concaved plate 19 disposable against the chin of a corpse. A set screw 20 is threaded into the block 16 and intersects the hole 17 for the purpose of clamping the shank 18 at any desired 65 position.

In the use of the device the yoke is placed about the neck of the cadaver with the hinge connection of the yoke sections at the back of the neck and with the arms of the yoke 70 extending above the shoulders and over the chest. The cross bar 13 is placed in position upon the yoke and the set screws 15 are tightened to maintain this adjustment. The block member 16 is then slid along the cross 75 bar if necessary or is turned to the desired position to bring the chin support proper in correct position so that the plate 19 engaging the chin will engage the chin at the most advantageous location. By adjusting the position of the shank 18 through the block 16, it is apparent that the head 80 may be forced backwardly to a greater or less extent or may be allowed to come forwardly toward the chest. In case it should 85 be desired to hold the head slightly to either side, it is apparent that this may be accomplished by sliding the block member 16 somewhat toward either end of the cross bar 13. It is probably preferable that the 90 block 16 should fit fairly closely upon the cross bar to prevent too great freedom of movement.

From the foregoing description and a study of the drawing it will be apparent 95 that I have thus provided a simple and yet highly efficient chin supporting device which is easily adjustable to meet varying conditions or to permit carrying out any necessary manipulations incidental to the 100 undertaking art. It is also to be noted that all the parts of the device may be readily disassembled and packed in a very small space for convenience in transportation or storage.

105 While I have shown and described the preferred embodiment of my invention, it is of course to be understood that I reserve the right to make such changes in the form, construction and arrangement of parts as 110

will not depart from the spirit of the invention or the scope of the subjoined claims.

Having thus described my invention, I claim:

- 5 1. A jaw setting or chin supporting appliance for the use of undertakers, comprising a yoke of rigid material having its bight portion engaging the back of the neck of a corpse and having its arms disposable over the chest, a cross bar slidably adjustably secured upon the arms of the yoke, a block member movably mounted upon said cross bar, and a chin support proper including a curved shank slidably adjustably connected with said block member and carrying a chin or jaw engaging plate.
- 10 2. A device of the character described comprising a yoke of rigid material, a cross
- 15

bar slidably adjustably connected with the arms of the yoke, a block member rotatably mounted upon said cross bar, and a chin support proper including a shank slidably adjustably connected with said block member.

20 3. A device of the character described comprising a yoke of rigid material, a cross bar slidably adjustably connected with the arms of the yoke, a block member rotatably mounted upon said cross bar, and a chin support proper including a shank slidably adjustably connected with said block member, said block member being also slidably along said cross bar.

25 In testimony whereof I hereto affix my signature.

30 MICHAEL E. BRENNAN.
